(57) **CLAIM**

The ornamental design for a ball organizer, as shown and described.

DESCRIPTION

FIG. 1 is a front perspective view of a first embodiment of the ball organizer of the present invention, from the left side;

FIG. 2 is a front perspective view of the ball organizer of FIG. 1, from the right side;

FIG. 3 is a rear perspective view of the ball organizer of FIG. 1, from the right side;

FIG. 4 is a right side elevation of the ball organizer of FIG. 1;

FIG. 5 is a rear elevation of the ball organizer of FIG. 1;

FIG. 6 is a left side elevation of the ball organizer of FIG. 1;

FIG. 7 is a top plan view of the ball organizer of FIG. 1;

FIG. 8 is a bottom plan view of the ball organizer of FIG. 1;

FIG. 9 is a front perspective view of a second embodiment of the ball organizer of the present invention, from the left side;

FIG. 10 is a front perspective view of the ball organizer of FIG. 9, from the right side;

FIG. 11 is a rear perspective view of the ball organizer of FIG. 9, from the right side;

FIG. 12 is a right side elevation of the ball organizer of FIG. 9;

FIG. 13 is a rear elevation of the ball organizer of FIG. 9;

FIG. 14 is a left side elevation of the ball organizer of FIG. 9;

FIG. 15 is a top plan view of the ball organizer of FIG. 9; and, FIG. 16 is a bottom plan view of the ball organizer of FIG. 9.
